2 Claims. (Cl. 167—65)

The present invention is concerned with new anti-anaphylactic compositions.

Using the test procedure outlined by Herxheimer, J. Physiol., 117, 251 (1952), we have found that the lower alkanolamines and compounds derived therefrom possess valuable anti-anaphylactic activity when administered experimentally to guinea pigs. These alkanolamine compounds can be administered in simple vehicles, such as distilled water, or in more elaborate vehicles, such as tablet bases. These alkanolamine compounds produce a protective action which can be observed as an increase in the time in which sensitized animals can tolerate an antigen without undergoing anaphylactic shock.

We have found that the protective action obtained by the use of these alkanolamine compounds is not very great when they are administered on their own but when administered in conjunction with known anti-histaminics which themselves only have a slight protective action, a considerable potentiation of activity is obtained. We have also found that a potentiation of the activity of these alkanolamine compounds is achieved when they are combined with expectorants, anti-tussives, anti-histaminics, anti-asthmatics, bronchodilators, corticosteroids, anti-biotics, bactericidals, bacteriostatics and/or anti-inflammatory agents.

This discovery has obvious valuable clinical applications since the compositions should be of considerable value in the treatment of allergic conditions, such as asthma, urticaria or conditions in which some allergic mechanism represents a contributory factor.

The low molecular weight alkanolamines which are used according to the present invention may be represented by the general formula:

wherein R₁, R₂ and R₃, which may be same or different, are hydrogen atoms or methyl or ethyl radicals; and the esters, salts, amides and quaternary ammonium salts thereof.

Examples of compounds which may be added to the alkanolamines are ipecacuanha and cocillana (i.e., expectorants), codeine and pholcodine (i.e., anti-tussives), "mepyramine" maleate and phenindamine tartrate (i.e., anti-histaminics), adrenaline and ephedrine (i.e., anti-asthmatics), prednisone and triamcinolone (i.e., corticosteroids and corticosteroid-like compounds), tetracycline and chloramphenicol (i.e., antibiotics), creosote and "cetrimide" B.P. (i.e., bactericides), "domiphen" bromide and benzalkonium chloride (i.e., bacteriostatics), aspirin, cortisone), xanthoglabrol, glycyrrhetic acid and derivatives thereof (i.e., anti-inflammatory agents), and xanthines and ephedrine (i.e., bronchodilators). "Mepyramine" is 2-[2-dimethylamino-ethyl](p-methoxybenzyl)-amino]-pyridine; "domiphen" is dodecyldimethyl-(2-phenoxy-ethyl)ammonium bromide; and "cetrimide" is cetyltrimethylammonium bromide. The compositions according to the present invention, which have been shown to exhibit true synergism, may be made up in the form of inhalations, aerosols, tablets, injections, onematas, suppositories, ointments, lotions and suspensions by admix-

ture with an appropriate solid or liquid pharmaceutical carrier or diluent.

Examples of alkanolamines coming within the scope of the above general formula are ethanolamine, N-methyl-ethanolamine, N,N-dimethyl-ethanolamine, choline, N-ethyl-ethanolamine, N,N-diethyl-ethanolamine, N,N,N-triethyl-N-ethylol ammonium salts, N-methyl-2-amino-propanol, N,N-dimethyl-2-amino-propanol, 2-aminopropanol, N,N,N-trimethyl-N-(2-propylol) ammonium salts, phosphatidyl-ethanolamine and ethanolamine phosphatase.

It is thought that the mechanism of the synergism of the alkanolamines of the above general formula and, for example, anti-histamines, can be outlined as follows: in 1956 Brocklehurst described at the Ciba foundation symposium on histamine, the liberation from sensitized guinea pig lung of two active principles which can be described as chemical mediators of anaphylaxis. He described these chemical mediators as histamine and the slow reacting substances of anaphylaxis (SRS/A). We have shown experimentally that alkanolamines and derivatives thereof of the above given general formula are capable of preventing the release of SRS/A in anaphylaxis. They have a negligible effect on the release of histamine in the same condition and it is, therefore, concluded that the histamine which is released in anaphylaxis is effectively controlled by the anti-histamine contained in the composition and that the alkanolamine derivatives potentiate this action by preventing the release of SRS/A, which is, for example, normally responsible for bronchospasm, even in the presence of anti-histamine molecules which are incapable of antagonising the pharmacological action of SRS/A.

We have also found that synergism exists between the alkanolamines according to the present invention and blood pressure-reducing drugs, such as pentaerythritol tetranitrate, diuretic drugs, such as acetazolamide and chlorothiazide, and anti-coagulant drugs, such as phenindione. Such compositions may be used, for example, in the treatment of arteriosclerosis and coronary thromboses.

The following examples are given for the purpose of illustrating the present invention.

(1) Inhalation:

500 mg. antazolidine sulphate
 1000 mg. ethanolamine hydrochloride
 900 mg. sodium chloride
 9000 mg. friar's balsam
 100 ml. water

1 tablespoonful is added to about 1/2 pint hot water and the vapours given off are inhaled.

(2) Tablet:

25 mg. mepyramine maleate
 5 mg. choline hydrochloride incipient, q.s.
 Fiat tabella.

(3) Injection:

200 mg. diphenylhydramine hydrochloride
 1000 mg. ethyanolamine succinate
 900 mg. sodium chloride
 100 ml. distilled water
 900 mg. domiphen bromide

The resultant solution is sterilized by heating for 30 minutes at 120° C. 1 cc. of the sterilized solution is injected as required.

(4) Enema:

200 mg. ethanolamine maleate
 100 mg. mepyramine maleate
 135 mg. sodium chloride
 10 mg. prednisolone phosphate
 150 ml. distilled water
 0.1% w/w. cetrimide

(5) Suppository:

3 g. chloramphenicol
 6 g. choline hydrochloride

- Q.s. cocoa butter
Fiat to mould 30 suppositories.
- (6) Ointment:
2 g. benzalkonium chloride
1 g. glycyrrhetic acid
5 g. ethanolamine hydrochloride
Ad 100 g. water-miscible ointment base
- (7) Lotion:
200 mg. glycyrrhetic acid hemisuccinate, disodium salt
1000 mg. ethanolamine maleate
900 mg. sodium chloride
900 mg. domiphen bromide
100 ml. distilled water

What we claim is:

1. A tablet consisting essentially of 1 part by weight of 2 - [(2 - dimethylamino - ethyl)(p - methoxybenzyl) - amino] - pyridine maleate and 2 parts by weight of choline hydrochloride.
2. Anti-anaphylactic composition of matter consisting essentially of 2-5 parts by weight of a member selected from the group consisting of alkanolamines of the formula

and the pharmaceutically acceptable quaternary ammonium salts and pharmaceutically acceptable bases thereof, in which R_1 is a member selected from the group consisting of hydrogen, methyl and ethyl, R_2 is a member selected from the group consisting of hydrogen, methyl and ethyl, and R_3 is a member selected from the group consisting of hydrogen, methyl and ethyl and one part by weight of 2 - [(2 - dimethylamino - ethyl)(p - methoxybenzyl) - amino] - pyridine maleate, in admixture with a pharmaceutical carrier.
